CLAIM

The ornamental design for a flower pot cover, as shown and described.

DESCRIPTION

FIG. 1 is a perspective view of a flower pot cover showing my new design;

FIG. 2 is a top plan view thereof;

FIG. 3 is a bottom plan view thereof;

FIG. 4 is a side elevational view thereof, all sides being identical; and,

FIG. 5 is an enlarged plan view of the lace pattern shown in FIG. 4.

The lace pattern as fragmentarily shown in FIGS. 1, 3, and 4 is understood to repeat uniformly across the circumscribed surfaces and represents the lace pattern shown in FIG. 5.

The flower pot cover has no substantial thickness.
